ARTICLE OF JEWELRY

Louis Garfinkel, Providence, R. I.

Application December 28, 1936, Serial No. 117,743

4 Claims. (Cl. 63—20)

The present invention relates to improvements in combination bar-pins and clip-brooches of the type illustrated and described in my copending application, Serial No. 92,168 filed July 23, 1936, which application has issued as Letters Patent Number 2,099,730.

One of the objects of the present invention is to provide an article of the type indicated in which the ornaments are freely slideable onto a supporting member and automatically locked in position thereon.

Another object of the invention is to provide an article of the type indicated having interengaging means so constructed as to permit the ornament to freely slide into position on the supporting member and to positively lock the ornament against movement in the opposite direction.

Another object of the invention is to provide an article of the type indicated in which the ornament can only be removed from the supporting member by manually releasing the locking means.

Still another object of the invention is to provide an article of the type indicated having a simple and compact structure of highly ornamental appearance, adapted to be economically manufactured from metal stampings, and with the ornaments capable of being easily and quickly assembled and locked on either a bar-pin or clip.

Further objects of the invention are set forth in the following specification which describes a preferred form of construction of the article, by way of example, as illustrated by the accompanying drawing. In the drawing:

Fig. 1 is a plan view of a bar-pin embodying a pair of ornaments mounted in juxtaposition on a supporting member;

Fig. 2 is a rear view of the bar-pin showing the means for attaching the ornaments to and locking them on the supporting member;

Fig. 3 is a longitudinal sectional view on line 3—3 of Fig. 2 showing the detent-shoulders on the spring-pressed tongue of the supporting member in locking engagement with the lugs on the ornament;

Fig. 4 is a view similar to Fig. 3 showing the curved cam-face on the tongue engaged by the lug on the ornament to depress the tongue as the ornament is slid into position on the supporting member;

Fig. 5 is a transverse sectional view on line 5—5 of Fig. 3 showing the relationship of the parts of the locking means in end elevation;

Fig. 6 is a perspective view of the bar-pin and

one of the ornaments in disassembled aligned relationship; and

Fig. 7 is a sectional view of a clip-brooch with an interchangeable ornament mounted thereon.

In the combination bar-pin and clip-brooch illustrated and described in my prior application, referred to above, the ornaments are resiliently latched in position on the supporting member. Although such a construction is quite satisfactory and has met with public approval, it is possible for the ornaments to become detached from the bar-pin or clip and lost. This is particularly true if the resilient tongue is bent or deformed or if the parts become worn.

The present invention provides interengaging means for positively locking the ornaments in position on their supporting member. The arrangement is such that the ornaments may be easily and quickly assembled on either the bar-pin or clips by merely sliding them into position thereon without any appreciable resistance. After the ornament is in position a resiliently-operated detent or shoulder on one part moves into interlocking engagement with a shouldered abutment on the opposite part to positively lock the ornament in position to prevent its accidental removal or displacement. After the shoulders on the opposite parts of the article have interlocked the ornament can only be removed by manually depressing the resilient detent-element to release the shoulders from interlocking engagement.

Referring to the drawing, the bar-pin is herein illustrated as comprising an ornament-supporting member in the form of a flat plate 2 having ears 3 at one end for hingedly mounting a pin-stem 4; and a keeper 5 at its opposite end provided with a safety catch 6. The plate 2 is preferably stamped from resilient sheet-metal stock to form a rectangular central portion 7 and narrower wings 8 extending therefrom with shoulders 9 therebetween. During the stamping operation portions of the plate are punched out to provide resilient tongues 12 connected at the outer ends of the wings 8 and extending inwardly toward the center. The tongues 12 are preferably in the form of narrow strips 13 which are bent outwardly away from the plane of the plate 2 and formed in any desired configuration to give the necessary stiffness and resiliency. The inward free ends of the tongues 12 project laterally of the narrow strip 13 and are deformed to provide right-angular shoulders or abutments 14 and offset lips 15 forming stops. As herein illustrated the tongues 12 are apertured at the center of the

deformed portions so that the shoulders 14 are disposed at the opposite lateral extensions of the tongues; but it will be understood that the shoulders may extend throughout the full width of the 5 tongues. At the rear of the shoulders 14 and at the opposite sides of the narrow strip 13 the material of the tongue is curved to form cam-faces 16 for a purpose as will later appear.

The interchangeable ornaments 20 may take 10 any desired form or configuration being herein illustrated as comprising pierced settings for brilliants, jewels or the like provided with guideways 21 on their rearward faces adapted to slide over the wings 8 of the supporting member 2 of the 15 bar-pin. Each guideway may be formed by slotting the material of the ornament or in any other manner; being herein illustrated as comprising a struck-up plate 22 soldered or otherwise attached to the back of the ornament. The plate 22 has side extensions folded around to form spaced channels 23 which terminate short of the end of the plate to provide a narrower flat extension or lip 24. Integral with the side extensions forming the channels 25 are lugs 25 which are folded inwardly to overlie the guideway 21. The sides of the lugs 25 extend at right-angles to the guideway 21 and form abutments for locking engagement with the shoulders 14 on the resilient tongues 30 12 as will presently more fully appear.

An ornament 20 may be mounted on one of the wings 8 of the supporting member 2 by first placing the lip 24 of the guideway plate 22 against the end portion of one of the wings 35 8 with its channels 23 in alignment with the side edges of the wing. The ornament 20 may then be bodily slid longitudinally of the supporting member 2 toward its center. During 40 the sliding movement of the ornament 20 with respect to the supporting member 2 the opposite inwardly-projecting lugs 25 engage the curved cam-faces 16 on the lateral extensions of the tongue 12 and cause the latter to be depressed to slide thereunder. At the end of the sliding movement the ends of the channels 23 engage the shoulders 9 on the supporting member 2, at which time the right-angular shoulders 14 on the tongue 12 are aligned with the rearward sides of the lugs 25. Due to the inherent resiliency of 45 the tongue 12 the latter snaps outwardly from the plane of the supporting member 2 at right-angles to the direction of the sliding movement so that the shoulders 14 are positioned at the rear of the lugs 25 in abutting engagement therewith. The outward movement of the tongue 12 is limited by the engagement of the offset lip 50 15 with the under side of the lugs 25.

The ornament 20 is thus positively locked to the supporting member 2 and is prevented from 55 sliding movement thereon in either direction. Another ornament 20 of the same type may be slid over the opposite wing 8 of the member 2 in the manner as above explained and in juxtaposition with the first ornament to form 60 an assembled brooch such as illustrated in Fig. 1.

To detach the ornaments 20 from the bar-pin or supporting member 2 it is necessary to manually depress the resilient tongues 12 to disengage the shoulders 14 from the abutments or lugs 70 25 on the ornament. The ornaments may then be slid off the supporting member 2 in a manner similar to that in which they were mounted thereon. However, after the ornaments 20 have once been mounted in position on the supporting bar-pin 2 they are positively locked in posi-

tion and cannot be unintentionally or accidentally detached so that any possibility of the ornaments becoming lost is eliminated.

Fig. 7 illustrates a clip 30 which is adapted to mount one of the interchangeable ornaments 5 described above. The clip 30 is of usual construction comprising a pair of leaves 31 and 32 hinged together by the pivot-pin 33. The leaf 31 is provided with projecting prongs 34 for gripping an article of apparel and a spring-finger 35 for resiliently holding it in either open or closed position with respect to the leaf 32. The leaf 32 is of a construction similar to the wings 8 of the supporting member 2 of the bar-pin previously described, having a resilient tongue 15 36 provided with right-angular shoulders 37 adjacent its free end.

When it is desired to apply one of the ornaments 20 to the clip 30 to form a clip-brooch the ornament is detached from the supporting member 2 of the bar-pin and mounted on the leaf 32 of the clip 30 in the manner as previously explained. To this end the leaf 32 of the clip 30 is positioned on the lip 24 of the ornament with its opposite sides in alignment 25 with the channels 23. The ornament is then slid longitudinally of the leaf 32 until the shoulders 37 pass by the lugs 25 and snap into locking engagement therewith, a suitable stop being provided on the leaf 32 to limit the movement 30 of the ornament 20 thereon. As explained with respect to the bar-pin, after the shoulders 37 interlock with the lugs or abutments 25 the ornament cannot be removed except by manually depressing the resilient tongue 36. With the leaf 35 31 in the position illustrated in Fig. 7 the clip may be attached to an article of clothing by merely pressing the two leaves together. The spring-finger 35 acting against a suitable abutment on the hinge causes the leaf 31 to snap 40 into closed position with respect to the leaf 32 to grip the prongs 34 against the clothing.

A preferred form of construction of the article having now been described in detail, it will be understood that various modifications may 45 be made in the structure and arrangement of its parts within the scope of the invention. For example, the channel plate may be on the bar-pin or clip for cooperation with a rectangular plate on the ornament, and the resilient latching tongue may be on the ornament for cooperation with lugs or other forms of abutments on the bar-pin or clip. The resilient tongue may also be a separate element attached to the plate instead of being integrally formed as illustrated. 55

It will be observed from the foregoing that the invention provides a novel form of combined bar-pin and clip-brooch in which a single interchangeable ornament may be mounted on a clip or a plurality of the ornaments mounted in juxtaposition on a bar-pin. It will also be observed that novel construction of the ornament and supporting members provide for convenient attachment of the ornament to and its detachment from the supporting members and for positively locking the two parts in assembled relationship. It will also be observed that a simple and compact structure has been provided which may be economically manufactured.

While the invention is herein described and illustrated as embodied in a preferred form of construction, it is to be understood that modifications may be made in the structure and arrangement of its parts without departing from the 70 75

spirit or scope of the invention. Therefore, without limiting myself in this respect, I claim:

1. An article of jewelry comprising a supporting plate, an ornament having a plate with the edge portions thereof folded around to form spaced channels for slidably mounting the ornament on the supporting plate, and interengaging means for positively locking the ornament in position on the supporting plate, said interengaging means comprising detents on the ornament having shoulders overlying the opening between the channels and a resilient tongue on the plate adapted to slide by the detents in one direction and having shoulders for engaging the shoulders on the detents to prevent movement in the opposite direction.
2. An article of jewelry comprising a supporting plate of resilient material apertured to form a tongue projecting outwardly from the plane of the plate and the tongue bent to form a right-angular shoulder, an ornament having a guideway, said supporting plate being slidable in the guideway on the ornament, and interengaging means comprising lugs on the ornament overlying the guideway and adapted to be engaged by the shoulder on the resilient tongue of the supporting plate, said resilient tongue maintaining its shoulders in engagement with the sides of the lugs whereby to prevent the ornament from being slid off from the supporting plate.
3. An article of jewelry comprising a support-

ing plate having a resilient tongue projecting outwardly from the plane thereof, said tongue having a curved portion terminating in a right-angular shoulder, an ornament having spaced channels forming a guideway and inwardly-directed lugs overlying the guideway, said supporting member being slidable in the guideway on the ornament and said lugs engaging the curved portion of the tongue to depress the latter until the shoulders slide past the lugs, the shoulders on the tongue thereafter engaging the lugs to positively lock the ornament in position on the supporting plate.

4. An article of jewelry comprising a supporting plate with a cut-out portion forming a resilient tongue extending from one end toward the center and projecting outwardly from the plane of the plate, said tongue having lateral extensions with curved portions terminating in right-angular shoulders, an ornament having a plate with its edge portions folded around to form spaced channels and provided with inwardly-extending lugs, said channel plate being slidable onto the supporting plate and said lugs engaging the curved portion on the lateral extensions of the tongue to depress the latter to permit the shoulders to slide past the lugs, the shoulders on the tongue thereafter engaging the lugs to positively lock the ornament against movement in the opposite direction.
